United States Patent Office.

ADOLPHE GAUDRON, OF DETROIT, MICHIGAN.

Letters Patent No. 93,873, dated August 17, 1869.

IMPROVEMENT IN SAWING-MACHINES.

The Schedule referred to in these Letters Patent and making part of the same.

To all whom it may concern:

Be it known that I, ADOLPHE GAUDRON, of Detroit, in the county of Wayne, in the State of Michigan, have invented a new and useful Improvement on a Hand-Power Sawing-Machine, designed to take the place of the ordinary buck-saw and horse, and applicable, also, to other purposes; and I do hereby declare that the following is a full and exact description thereof, reference being had to the accompanying drawings, and to the letters of reference marked thereon, making a part of this specification.

The nature of my invention is the combination of the machinery for feeding and raising the saws, when the log is cut, and the arrangement of the dog grasping the log on the horse.

To enable others skilled in the art to make and use my invention, I will proceed to describe its construction and operation.

My machine is constructed of a wood frame, A, to which the machinery is fixed, and arranged to work with two saws, one on each side.

A motive-wheel, B, is placed inside of the frame A, mounted on a shaft, K, projecting from both sides of the frame, to which is adapted a crank, C, to be worked by hand.

There are a fly-wheel, D, and pulley, E, mounted on the shaft K', with a crank, F, at each end, giving motion to the saws H and H', by means of the connecting-rods G G'.

The belt I transmits motion from the wheel B to the crank F, which, by the connecting-rods G G', transmits the oscillating motion to the saws H H', which are attached to the frame J J', mounted on a projecting centre-pin, K". (See section, Figures 5, 6, 7.)

The pin K" works in a frame, L, sliding between two slides, M M', inside of which is a ratchet-bar.

Two pawls, N N', work on a pin fixed to the piece O, screwed through the middle of the centre-pin K".

The piece O can be raised or lowered, to regulate the motion of the pawls with the ratchets, according to the oscillation of the saws.

A plate, P, with an oblong slot, slides up and down between two pins, Q Q'.

The plate P, by going up, throws out the pawls N N' of the ratchets with the two pins R R'. By coming down, the pawls N N' become free, and the spring S brings them into the ratchets.

The plate P is connected to a bar, T, a bell-crank, U, and rod, V.

A spring, X, is supported and fixed to the upper end of the rod V, and to the frame A by the lower end.

By that combination the spring X, pulling the upper arm of the bell-crank U, will raise the saw to the upper position, when the pawls are thrown out of the ratchet-teeth.

I will describe the use of the dog a, Figures 1, 2, intended to grasp the log on the horse.

By pulling the handle b, the teeth of the ratchet c catch the hook d, Figures 2, 3.

As soon as ready to put on another log, by pressing with the foot on the treadle e e', it pulls down the hook d, by the wire f, and the ratchet-bar is free.

The spring g brings back the arm of the dog a.

A spring, h, keeps up the hook d.

Now I will explain how to work with my machine.

It can be worked with the two saws at once, or one after the other, without removing any piece.

The space between the saws is sixteen inches, dividing the log of cord-wood in three.

If only one cut is required, the middle of the log is put under one of the saws.

The first operation is to put the log on the horse; then, to pull the handle b of the dog a enough to grasp the log firmly.

The second operation is, after taking hold of the hand-crank O with one hand, to begin motion of the saws, to push the upper arm of the bell-crank U, in order to drop the saw on the log as soon as the plate P is brought down, by means of the inclined bar T.

The notch Y catches the pin Q, fig. 5, and the pawls N N' fall in the ratchets.

The machine being put in motion, the oscillation of the saws transmits motion to the centre-pin K, and the pawls will catch the teeth of the ratchets, one after the other, bringing down the saws, until it has passed the log.

Then the lower part of the plate P, which is rounded, strikes against the dog Z, fig. 2, which throws the notch Y out of the pin Q, by pushing it to the opposite side.

At the same moment the spring X pulls the upper arm of the bell-crank U, which raises the plate P, by means of the bar T. In the mean time the pins R R' throw the pawls N N' out of the ratchet-teeth, and the spring X, by pulling, raises the saws freely to their upper position, ready to begin again.

What I claim as my invention, and desire to secure by Letters Patent, is—

1. The apparatus by which the saws are raised when the cutting is done, constructed and operating as herein set forth.

2. The connecting-rod G, in combination with the saws H H', their frames J J', the different pieces on the plates P and L, connecting-rod T, the bell-crank U, the bars V, with their springs X, all constructed substantially as herein set forth.

3. The dog a, in combination with the pieces c d and e f h g, constructed in the manner herein shown and described.
